Scow having port and starboard pockets hinged and locked to a centrally located bridge, with bow and stern pontoons fixed at the ends, thus the bridge and perpendicular pontoons in plan form an H, providing two recesses for housing the pockets.

Scow having a longitudinal bridge fixed to the ends of the scow, the bridge having a central longitudinal bridge, with port and starboard pockets hinged and locked to the bridge, with bow and stern pontoons fixed at the ends, thus the bridge and perpendicular pontoons in plan form an H, providing two recesses for housing the pockets.

UNITED STATES PATENT OFFICE

2,444,299

DUMPING SCOW

Louis R. Koenig, New York, N. Y.

Application February 26, 1946, Serial No. 650,197

3 Claims. (Cl. 114—29)

1 This invention relates to a dumping-scow having port and starboard pockets hinged and locked to a centrally located bridge, with bow and stern pontoons fixed at the ends, thus the bridge and perpendicular pontoons in plan form an H, providing two recesses for housing the pockets.

The primary object of the invention is to provide a self-dumping, automatic closing, dumping-scow for transporting mud and other heavy material to sea, or other disposal area.

Loaded pockets are released simultaneously and will pivot downwardly under water from horizontal to vertical positions discharging the material to both sides aided by gravity, and the inrush of water scours the pockets. When water has become static, the deck of the pontoons and the bridge rise above the surface of the water, and the pockets pivot upwardly against gravity, due to the air-compartments built into the outer walls of the sloping sides of the pockets, returning and locking themselves into their original horizontal positions. While pivoting upward the pockets perform outward scooping motions, that tend to eject the water from said pockets.

Other objects of the invention will become apparent from the following specification, the drawings and from the claims.

In the drawings:

Fig. 1 is a perspective drawing showing the parts comprising the bow and stern pontoons fixed to the bridge fore and aft, and the port and starboard pockets. Broken away area shows section below deck.

Fig. 2 shows a perspective drawing of the forward part of the bridge deck with a part broken away to show the apparatus for locking the pockets.

Fig. 3 is a side elevation of the forward end of the scow with the port side pocket in a dumping vertical position.

Fig. 4 is a transverse vertical section taken at line 4—4 of Fig. 1 showing pockets in vertical dumping positions.

Fig. 5 is a transverse vertical section taken at line 4—4 showing pockets in horizontal, closed positions.

Similar numerals refer to similar parts throughout the specifications and drawings.

In Figure 1, the component parts of the scow show bow pontoon 10 and stern pontoon 11, fixed to the ends of the centrally located longitudinal bridge 12; with the port side pocket 13 and the starboard pocket 14 hinged to the lower sides of

the bridge walls 36 and 37, at 15 and 16, in line with the bottom wall 31. The bridge 12, and the perpendicularly fixed pontoons 10 and 11 in plan form an H, which provides the two recesses wherein the pockets 13 and 14 are housed, and locked when empty, and before loading the scow.

The said pockets 13 and 14 have only top-side openings for loading, or depositing the material therein; and from which the material is subsequently discharged by drawing bolt 21, which releases the catches 19 shown in Figure 2 and that allows the pockets 13 and 14 to pivot on hinges 15 and 16 from horizontal to vertical positions as shown in Figures 5 to 4, taken at line 2—2 of Figure 1. The bottom walls of the pontoons 10 and 11, and the bottom walls of the pockets 13 and 14, shall be at the same plane, but the bottom wall 31 of the bridge 12, must be above the bottom walls of the pockets 23 and 24 as shown in Figure 5, a difference equal to one half the width of the bottom 31 of the bridge, or vice versa, the bottom wall of the bridge 31 must be at least twice the difference between the bottom wall of the bridge 31 and the bottom walls of the pockets 23 and 24, in order that when the pockets 13 and 14 as shown in Figure 5 are to be dumped the pockets may pivot downwardly, and the bottoms 23 and 24 of said pockets can tilt under the bridge and meet in vertical positions as shown in Figure 4, thus permitting the material to be discharged by gravity, aided by the inrush of water into the pockets 13 and 14, which also scours the pockets of any material, before the buoyancy of the air-compartments contained in the outer walls 25 and 16 of the pockets 13 and 14, pivot upwardly from vertical to horizontal positions against gravity; while in so doing, both pockets perform scooping motions ejecting the water within the pockets to both sides, as the scow rises on the surface of the water. When the cycle of the various actions have been completed, the scow when empty will again assume the status as before loading, or while being loaded, as shown in Figure 1 and Figure 5.

In Figure 1, are shown three bulkheads 29 in each pocket making four compartments, there may however be more or less number of compartments and bulkheads 29, depending upon the length of the scow and the pockets 13 and 14. These bulkheads tend to brace and reinforce the pockets 13 and 14, when the scow is loaded, and while in transit.

The scow should be built of metal, prefer-

ably of alloy steel sheets and structural shapes, that are non-corrosive, or nearly so. The sloping inner sides 27 and 28 of the outer walls 34 and 35 of the pockets 13 and 14, should have chrome or other non-abrasive surfaces to accelerate the rapid, non-adhesive sliding discharge of any material when dumping the pockets 13 and 14 as shown in downward vertical positions in Figure 4.

In Figure 2 is shown a locking arrangement to retain the pockets in horizontal positions when the scow is light or empty, and while being loaded or in transit as shown in Figure 1, and in the transverse vertical section Figure 5. In the perspective drawing Figure 2 is shown the forward or bow section of the bridge 12 with the end of the draw-bolt 21 extending out from under the deck 30, of the bridge 12, which also appears at a reduced scale in Figure 1. Indicated by line 4-4 of Fig. 2, shown at and about line 4-4 the broken away area in the deck 30, of the bridge 12, shows the arrangement wherein the draw-bolt 21 when drawn out by a hawser from the tug-boat, or by some mechanical power aboard the scow, will also advance the pin 22, which is fixed to the center line of the bolt 21, and extends above and below the draw-bolt through the slots shown at 22. The said slots being provided to allow the pin 22 to travel back and forth when the bolt is drawn or returned to its normal position. When the bolt 21 is drawn the latch bars 17 act as levers about the stumps 18, forcing back the compression springs 20, and disengage the catches 19, unlocking the pockets 13 and 14 from their horizontal positions. The draw-bolt then released, immediately returns with the latch bars 17 to their normal positions, as shown in Figure 2. When the process of dumping has been completed, and the pockets 13 and 14 have pivoted upwardly to their original positions shown in Figures 1 and 5, the catches 19, which are welded to the back of the pocket walls 32 and 33 enter the rectangular openings provided in the upper part of the bridge walls 36 and 37 below the deck 30, to engage the hooked latch-bars by forcing back the compression springs 20, until the catch 19 and the hook of the latch 17 are engaged and held in that position by the compression springs until again released by the draw-bolt 21. The same locking units above described and located at a line 4-4 of Figure 1 and Figure 2, are also installed at line 3-3 and at line 2-2 of Figure 1. All the locking units are to be synchronized to operate simultaneously when the bolt 21 is drawn to discharge the material from the pockets 13 and 14, and the same will be so, when the pockets are discharged and return to their horizontal positions to be locked automatically.

In connection with the construction of this

scow, another locking arrangement may be used, if found to be of better advantage; the main object of this invention being to provide a dumping-scow that can be more conveniently operated, to save time and labor with less maintenance.

I claim:

1. A metallic dumping-scow having a centrally located longitudinal bridge and a bow and a stern pontoon fixed perpendicularly to the ends thereof thereby providing two recesses one on either side of the bridge, side pockets in each recess, means hingedly connecting the pockets to the bridge, and means locking said pockets in load receiving position.
- 15 2. In a dumping-scow having a central longitudinal bridge and perpendicular bow and stern pontoons fixed to the ends of the bridge thereby providing two recesses one the port and the other starboard, pockets hinged to the lower sides of the bridge in line with the bottom wall of the bridge, the dimensions of the pontoons, bridge, and pockets being so proportioned that the bottom wall of the bridge is above the plane of the bottom walls of the pontoon and the pockets by 20 a distance of not greater than the width of the bridge at its bottom, whereby the bottoms of the pockets may tilt from horizontal to vertical positions and approximately meet in the latter position during dumping.
- 25 3. In a dumping scow having a longitudinally extending centrally located bridge, bow and stern pontoons fixed to the ends thereof providing recesses on each side of the bridge and pockets hinge connected to the bridge in said recesses, buoyancy chambers in said pockets adjacent outer lower corners thereof, releasable means on the upper surface of the bridge locking said pockets in load retaining position, the lock means including spring catch devices on back of walls 30 of pockets adjacent said bridge, the release means including a bolt unit and a flexible element operable from a remote point to actuate said bolt to 35 permit dumping, the buoyancy chambers coacting with the hinge connection between the bridge and pocket to return the pocket to latched engagement after dumping.
